Primary Examiner — Bridget L Eland*(74) Attorney, Agent, or Firm* — Birch, Stewart, Kolasch & Birch, LLP(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is another front view thereof, showing environment in a state of use;

FIG. 7 is another front view thereof, showing environment in another state of use; and,

FIG. 8 is another front view thereof, showing environment in yet another state of use.

The dash-dot broken lines that are immediately adjacent to the claim represent the bounds of the claim, while all other broken lines are directed to environment; the broken lines form no part of the claimed design.
